(57) **CLAIM**

I claim the ornamental design for an ergonomic computer keyboard, as shown and described.

DESCRIPTION

FIG. 1 is a top plan view of an ergonomic computer keyboard according to the present invention.

FIG. 2 is a front elevation view of the ergonomic computer keyboard of FIG. 1.

FIG. 3 is a rear elevation view of the ergonomic computer keyboard of FIG. 1.

FIG. 4 is a bottom plan view of the ergonomic computer keyboard of FIG. 1.

FIG. 5 is a top perspective view of the ergonomic computer keyboard of FIG. 1.

FIG. 6 is a right elevation view of the ergonomic computer keyboard of FIG. 1; and,

FIG. 7 is a left side elevation view of the ergonomic computer keyboard of FIG. 1.
